EGG GRADING DEVICE

Otto Niederer, Titusville, N. J.

Application June 21, 1935, Serial No. 27,776

4 Claims. (Cl. 209—121)

This invention relates to a device for grading eggs.

In accordance with the present invention a simple and inexpensive device is provided whereby large quantities of eggs may be quickly and easily candled and graded by a single person.

In accordance with the present invention an inclined trackway is provided and down which the eggs in single file roll by gravity over a source of illumination for candling purposes; and at one end of the trackway scales are provided for grading the eggs according to weight and for directing the graded eggs into proper pockets or receptacles provided therefor.

The invention together with its objects and advantages will be best understood from a study of the following description taken in connection with the accompanying drawings wherein:

Figure 1 is a top plan view of the device.

Figure 2 is a side elevational view thereof.

Figures 3, 4 and 6 are detail sectional views taken substantially on the lines 3—3, 4—4 and 6—6 respectively of Figure 1.

Figure 5 is a top plan view of a grader scale.

Figure 7 is a transverse sectional view taken substantially on the line 7—7 of Figure 5.

Figure 8 is a longitudinal sectional view through a glass cylinder forming part of the grading scale.

Figure 9 is a side elevational view of a combination transfer rail and stop member.

Figure 10 is a top plan view of the combination transfer rail and stop member.

Figures 11 and 13 are sectional views taken substantially on the lines 11—11 and 13—13 respectively of Figure 10.

Figure 12 is a detail view taken substantially on the line 12—12 of Figure 9.

Figure 14 is a detail sectional view taken substantially on the line 14—14 of Figure 2.

Figure 15 is a fragmentary top plan view of a rail and supporting post therefor.

Referring to the drawings by reference numerals it will be seen that the candling and grading device comprises an elongated platform 1 supported by legs or standards 2. Supported on the platform is an inclined track 3 comprising a pair of round rails 4—4 supported above the platform post 5.

As best shown in Figure 14 the rails 4 are set in notches or recesses provided in the upper end of the post 5 and the rails of the track are supported at the desired elevation through the medium of upper and lower lock nuts 6 provided on

threaded ends of the post 5 that extend through apertures provided therefor in the platform 1.

Arranged underneath an intermediate portion of the trackway 3 is a casing 7 having openings 8 in the top thereof and arranged in alignment with the space between the rails 4. Suitably mounted in the casing 7 and in alignment with the openings 8 are electric lamps 9 (see Figures 1 and 2).

At the lower end of the trackway 3 is a transfer track indicated generally by the reference numeral 10.

As best shown in Figures 9 to 13 inclusive, the transfer track 10 comprises a pair of short spaced parallel round rails 11 having end portions welded or otherwise secured to the top of an inverted channel member 12.

Rigidly secured to the sides of the member 12 are one end of arms of substantially elongated L-shaped members 13 arranged in diverging relation as shown in Figure 10. The members 13 have vertical arms 14 disposed at opposite sides of the trackway 3 and these arms 14 are provided adjacent their upper end with vertically spaced notches with which is engaged an endless elastic stop band 15 with which the foremost egg shown in broken lines in Figure 2 and indicated by the reference numeral 16 abuts as for a purpose hereinafter made manifest.

Also secured to the member 12 is one end of a rod 17 that has a short upturned end 17a. This end 17a operates between the rails 4 to engage behind the foremost candled egg 16 to arrest the movement of the other eggs as the first mentioned egg passes under the elastic band 15 to roll down the trackway 3 and onto the transfer track 10.

As shown in Figure 11 the rod 17 adjacent the end 17a is supported by a strap 18 that extends between the members 13, which members, it will be noted are downwardly offset with regard to the plane of the member 12.

For limiting rotative movement of the trackway 10, which latter is supported for pivotal movement by post means 19 rising from the platform 1, there are provided stop rods 20, and 21 respectively secured at the desired adjustment on the platform 1 by lock nuts 22. In this connection and as best shown in Figure 2, the stop rod 20 is arranged in the path of the cross member 18 while the stop rod 21 is arranged in the path of the member 12. Also, on the member 12 there is secured to the underside thereof by a bolt and slot connection 23, a shiftable weight 24 which may be adjusted as found desirable for control.

ling the tilting movement of the trackway 10 incidental to the reception of an egg thereon from the trackway 3. Also arranged on the platform 1 are a plurality of relatively spaced bridge tracks 23, 24, 25 and 26 respectively. Any number of these bridge tracks may be provided and each is shown consisting of a pair of spaced apart round rails supported by posts equipped with stop nuts corresponding to the post 5 and lock nuts 22 forming the supporting means for the rail of the track switch.

Arranged in offset relation to the bridge tracks 23, 24, 25 and 26 are the track equipped ends of grading scales indicated generally by the reference numeral 27.

Each grading scale as best shown in Figure 1 and Figures 5 to 8 inclusive includes a balance bar 28 pivoted adjacent one end as at 29 to a suitable post 30 rising from the platform 1. Secured to the pivoted end of the bar 28 are the ends of bracket arms 31 that support a rigid frame embodying a pair of rails including an outer longer rail 32 and an inner shorter rail 33 aligning with the rails of the trackways 23, etc.

On the opposite side of the pivot 29 the bar 28 is provided with a slot 34 to accommodate a portion of a tube 35 of glass or other suitable transparency. The glass contains weights in the form of a ball 36 and is closed at its ends by suitable plugs 37, 38 respectively as shown in Figure 8. Also, the glass tube 35 is secured in position through the medium of a suitable strap 39 secured at its ends to the bar 28 by bolt and slot means 40. Thus the tube 35 may be secured at the desired longitudinal adjustment on the bar 28.

Rotative movement of the balancing lever 28 in a clockwise direction is limited by a suitable stop rod 41. Also, to secure the maintaining of the rails 32, 33 in a horizontal position at all times the innermost rail 33 is provided with a depending arm 42 to which is pivoted one end of a link 43 that is also pivoted between the post 30 provided for the balancing lever 28.

Also, associated with the rails of the grading scale is an inclined chute 44. In the present instance, the chute 44 as shown in Figure 4 is formed from a single piece of strap metal or the like having one end suitably formed by the standard 44a for the chute and this standard is secured to the platform 1 as at 45. The chute 44 is so arranged as to project upwardly between the rails of the associated scale when the latter is tipped by the weight of the egg thereon in a manner shown in Figure 4. Thus through the medium of the chute 44 the egg on the trackway of the scale is directed toward a slot 46 provided at the platform at the lower end of each chute 44.

Operating in the slot 46 and pivoted as at 47 is a chute 48 which is weighted at its pivoted end as at 49.

The chute 48 as suggested in Figure 3 serves to direct the graded eggs into the proper pockets 50 provided as shown in Figure 1. In this connection it will be noted that a plurality of pockets 50 are provided one for each of the scales 28 and these pockets are formed in what may be termed a lateral extension 51 provided for the platform at one end of the latter.

In connection with the above it will be understood that the tubes 35 of the scales 27 are so adjusted as to require an egg of a certain weight to tip the scale, as for example, the adjustment of the tube 35 on the first scale 27 is such that a relatively heavy egg will be required to tip that scale, while the adjustment for the next

adjacent scale is such that an egg of a slightly less weight will tip that scale, and so forth so that the eggs may be rapidly graded according to size and weight.

The operation and utility of the device is thought to be apparent from the foregoing. The eggs as they roll down the inclined trackway 3 and pass over the lamp 9 are candled. To permit the first egg to pass from the lower end of the trackway 3 onto the transfer track 10 the latter 10 is tilted manually. Upon tilting of the trackway 10 in this manner the band 15 is raised to permit a second egg to pass thereunder while the end 17a of the member 17 will serve to arrest movement of the following egg. As will be appreciated, after the first egg has passed under the barrier 15 the hand will be removed from the trackway 10 permitting the latter to drop to its normal position so that the barrier 15 will take place of the end 17a of the member 17 for arresting the movement of the aforementioned following egg. As the first egg passes from the lower end of the trackway 3 and on to the transfer track 10, trackway 10 will again tilt, this time under the weight of the egg thereon so that the operation above explained with regard to the successive raising and lowering of the barrier 15 will be repeated. Manifestly such operation will be successively repeated until all of the eggs have been candled.

As an egg passes from the trackway 10 it rolls onto the trackway 23 and from this trackway onto the trackway of the first scale 27. If the eggs are of sufficient weight the beam of this scale will then be tilted and the egg will be transferred from this scale through the medium of the chutes 44 and 48 in a manner previously described into the proper pocket 50. Obviously, if the egg is of lighter weight it will pass onto the trackway of the next scale, it being obvious that the scale will tilt to dispense the egg only when an egg of the proper weight passes onto the trackway of the scale.

In connection with the above it will be noted that my improved grading scale will work efficiently and quickly, the spherical wall 36 being freely movable within the transparent tube 35 working, in the first instance, to discharge the egg quickly as soon as the beam overbalances lightly, and in the second instance working to quickly return the balance beam to a balance or normal position when an egg of the proper weight has been removed from the scale in a manner hereinbefore clearly pointed out. Thus the scale will be quickly returned to proper position for receiving the next succeeding egg.

Working in unison with the scales is my improved transfer track and stop assembly associated therewith, said transfer track and stop means serving to properly time the feeding of the eggs to the scales. Further, by reason of the specific construction of the stop means and the engagement thereof with the eggs, sufficient rotary movement is imparted to the eggs to insure a thorough and careful candling of the eggs.

From the above it will be apparent that with a device of this character, thorough and efficient candling of the eggs will result and that the parts are so timed in their operation that the eggs will be properly fed to the scales to insure a rapid yet proper grading thereof.

Having thus described the invention, what is claimed as new is:

1. In an egg grading device, an inclined trackway, a plurality of laterally spaced scales at the

lower end of the trackway, each scale being provided with a trackway in substantial alignment with the inclined trackway, a pivoted transfer trackway intermediate the lower end of the inclined trackway and the trackway of the first scale, means connected with the transfer trackway and movable therewith for controlling the movement of the eggs over the inclined trackway, a platform upon which said inclined trackway and scales are mounted, and said platform being provided with slots arranged in alternation relative to the scales, and chutes arranged in alternation to said slots and relative to the trackways of the scales for directing eggs on the tilted scales toward said slots.

2. In a device of the character described, the combination of a grading scale including a pivoted beam, a track mounted on one end of the beam including a pair of spaced apart rails, and an inclined chute fixedly mounted relative to the scale and adapted to project upwardly between the rails of the track upon a tilting of said beam.

3. In a device of the character described, and

in combination, a grading scale including a pivoted beam, a trackway on one end of the beam and extending transversely of the beam, and a fixed chute arranged to project upwardly between the rails of the trackway when the trackway equipped end of the beam is depressed whereby to direct an article on the trackway toward one end of the latter to discharge therefrom.

4. In a device of the character described, a fixed platform provided with a slot, a chute disposed at one side of the slot, a grading scale mounted on the platform and including a pivoted beam, a trackway mounted transversely on the beam at one end of the latter and movable downwardly with the beam to receive the chute between the rails of the trackway, said chute acting to direct an article on the trackway toward said slot for passage through the slot, a pocket arranged beneath the platform in operative position to the slot, and a second chute pivoted between the sides of said slot for guiding the article passing through the slot into said pocket.

OTTO NIEDERER.
